DECORATIVE PLATE AND MOUNTING

Norman J. Stupell, New York, N. Y., assignor to Signa-Craft, Inc., New York, N. Y., a corporation of New York

Application August 27, 1954, Serial No. 452,606

1 Claim. (Cl. 40—2)

The present invention relates to a decorated device and more particularly to the combination of a decorative or identification plate and a cooperating decorated object to which the plate is removably attached.

It is often desirable that objects such as keys, bracelets, compacts or others have a decorative or identifying monogram or emblem or other design on them. Affixation of such a design, however desirable, has frequently been impractical due to the difficulty of applying a satisfactory one at a low cost or by unskilled persons in a short time. Previously, designs have been applied by permanently cementing them on or by stenciling the design onto the object, or by cutting and engraving the design into the article. Permanent cement requires an appreciable drying time and generally makes it difficult to replace the decorative device. Stenciling and engraving are time consuming and require skilled craftsmen.

The present invention provides a monogram or identification device which is rapidly applied to the article by inexperienced persons, which is tightly retained during use of the article and which at the same time may be easily removed and replaced when desired.

An object of the invention is to provide a decorative device and a cooperating mounting.

Another object of the invention is to provide a readily attachable type of decorative plate and a mounting therefor.

Another object of the invention is to provide a detachable type of decorative device for use with a cooperating mounting surface.

Another object of the invention is to provide a mounting for a stay-wet adhesive type of decorative device.

Other and further objects of the invention will be obvious upon an understanding of the illustrative embodiment about to be described, or will be indicated in the appended claim, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a front elevational view of a key having the decorative device and mounting surface of the invention;

Fig. 2 is a sectional view taken along the line 2—2 of Fig. 1;

Fig. 3 is a sectional view taken along the line 3—3 of Fig. 1;

Fig. 4 is a perspective view of the key of Fig. 1 with the decorative device removed from its mounting and partially cut away; and

Fig. 5 is a front elevational view of a monogram type of decorative device.

Fig. 1, which illustrates one embodiment of the invention, shows a key 1 such as an auto key having a conventional operative portion 2 and a handle portion 4. Attached to the handle portion in a manner to be more fully described below is a name plate or decorative de-

2

vice 5. Device 5 may have the owner's initials or name on it, or it may have a distinctive design or an identifying label of any sort. Such markings are popular for identification purposes, for decoration and for the individualized look they give a decorated object.

The decorative device 5 itself will first be described. The device 5 is generally similar to that disclosed in the inventor's co-pending application S. N. 185,943, filed September 21, 1950, now Patent No. 2,699,618, dated January 18, 1955.

The device 5 comprises a relatively rigid plate 6 having an outer surface 7 bearing the decorative design or other insignia such as initial 16. The inner face 8 of the plate is provided with an adhesive means 9. In the preferred form, one of the so-called "wet adhesives" is used, such as a water insoluble rubber adhesive. Such adhesives retain their stickiness almost indefinitely and do not require the application of solvents before use as do "dry" adhesives or cement.

The adhesive means 9 preferably does not extend to the edges of plate 6 before plate 6 is pressed onto the key 1 so that the adhesive does not tend to squeeze out around the plate edges when the plate 6 is applied. Before the plate 6 is applied to the key, a layer of protective material 10 is releasably bonded to adhesive 9. This protective material is peeled off before the device is applied to the key.

Plate 5 preferably is made to have a convex outer surface 7 and a concave inner surface 8, as seen in the cross sections of Figs. 2 and 3. The advantages of this shape and the mounting surface on the key used therewith will be explained below.

A mounting surface 11 is provided on key handle 4 to firmly hold device 5 in place on key 1. Surface 11 has a central convex portion 12 shaped to generally correspond to the inner surface 8 of device 5. Around portion 12 is a narrow, flat edge portion 14 to accommodate the edges of device 5 and the excess adhesive 9 squeezed outwardly from the center portion of the device 5. Around this edge portion 14 is a raised rim 15 shaped to fit closely around the outer edge of device 5 and high enough to extend at least to the edge of surface 7 of plate 6 when plate 6 has been pressed into position on convex portion 12 of surface 11.

The curved and complementary shapes of plate 6 and convex portion 12 of key 1 provide a combination with the following advantages. The convex shape of surface 12 cooperates with the concave shape of the adhesive 9 to prevent lateral motion of the device 5 back and forth on the mounting surface 11. This aids in keeping device 5 firmly in place on any object provided with a mounting surface 11, however it is particularly important in the case of key 1. The pulling and turning motions on a key tend to move a decorative device 5. The raised convex surface 12 holds device 5 in position against such motions. The locking effect is increased in the case of a key, since the user grips tightly the handle portion 4 of the key, thus holding device 5 in position over convex portion 12.

Rim 15 used in the preferred embodiment extends at least to the surface 7 of plate 6 and thus also prevents lateral motion of device 5 across the handle 4 of key 1. Rim 15 also confines the spread of the adhesive 9 beneath the plate 6 and allows any excess adhesive forced outwardly from the plate to build up around and beneath the edges of plate 6 to prevent air from entering beneath the device 5. Thus, as the air is forced outwardly from under device 5 as it is squeezed in place and is prevented from returning by adhesive 9, a vacuum force is present on face 7 of device 5 to aid in holding it in place.

In addition to improving the attachment of the device 5 to the decorated object, the convex shape of device 5 is

preferable from a decorative standpoint, as it gives the decoration or other marking a solid three-dimensional look. This makes the device 5 appear more like an integral part of the decorated device and also makes the markings legible to the viewer from wider angles.

While the combined device 5 and mounting surface 11 are particularly useful on keys as described above in the convex form of the preferred embodiment, it is clear that the device may be used on other objects such as jewelry, containers and the like. In certain applications the device 5 and the cooperating surface 11 may have a generally flat shape where the increased adherence resulting from the convex shape of the preferred embodiment is not required.

It will be seen that the present invention provides an extremely useful and decorative combination. A detachable device is provided which may be readily applied to the decorated object and which remains firmly in place to resist accidental removal during usage. Dealers of the decorated article may keep a stock of the decorative devices on hand so that the initials or other mark desired by a purchaser may be affixed in a matter of seconds.

Where the device 5 is an identification, it may be readily changed in a few seconds to allow the article to be used by and identified with a new user. The stay-wet adhesive allows the decorative device to be readily applied or removed, and the shape of the device 5 and the cooperating mounting surface 11 and rim 15 combine to allow the stay-wet adhesive to hold the device 5 tightly in place both by adhesion and by vacuum force.

The preferred form also results in an attractive decoration which has a three-dimensional effect, making the marking very legible.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

A key provided with a decorative mounting comprising a curved plate having a convex outer face with a distinctive marking thereon and a concave inner face having a layer of adhesive thereon for attaching it to the key, said key having an operative portion and a handle portion, said handle portion having a convex mounting surface thereon shaped to fit the concave inner face of said plate and substantially coextensive therewith for mounting said plate on said key, said convex mounting surface having a rim at its edge, and the layer of adhesive on the inner face of the plate terminating short of said rim, whereby the plate will be prevented from moving laterally when the handle portion of the key is grasped for use and whereby the rim will obstruct flow of the adhesive.
